UNITED STATES PATENT OFFICE.

SAMUEL DARLING, OF WAUPUN, WISCONSIN.

ARCH-SUPPORT.

1,346,444.

Specification of Letters Patent. Patented July 13, 1920.

Application filed July 15, 1919. Serial No. 310,896.

To all whom it may concern:

Be it known that I, SAMUEL DARLING, a citizen of the United States, residing at Waupun, in the county of Fond du Lac and 5 State of Wisconsin, have invented certain new and useful Improvements in Arch-Supports; and I do hereby declare the following to be a full, clear, and exact description of the invention, such as will enable others 10 skilled in the art to which it appertains to make and use the same.

The present invention relates to improvements in arch supports, and it is an object of the present invention to provide an improved arch support built up in such a manner that it can be added to or its parts diminished in order that it may meet the needs of each particular foot and to accommodate it to any changes that may occur 20 during the treatment of the same foot.

It is another object of the present invention to provide an improved arch support in combination with a cushioned heel piece which gives increased flexibility to the device, thus accommodating the support to 25 the arch of the foot more comfortably; and this heel piece also further assists in keeping the arch support in the proper place, as the weight of the heel on such cushioned 30 piece will have the effect to anchor the support in place.

A further object of the present invention resides in providing an improved support that will be of improved flexibility, and the 35 flexibility of which may be either increased or lessened by the use of more or less standard parts.

In the accompanying drawings forming a part of this application, and in which similar reference symbols indicate corresponding parts in the several views:

Figure 1 is a perspective view of an improved arch support constructed in accordance with the present invention.

5 Fig. 2 is a plan view thereof with parts broken away to show the interior of the support.

Fig. 3 is a longitudinal sectional view through the improved support.

0 Fig. 4 is a transverse sectional view through same; and

Fig. 5 is a perspective view of one of the springs employed.

Fig. 6 is a side view of a laminated spring.

Referring now more particularly to the drawings, the improved arch support is preferably formed after the fashion indicated generally in Figs. 1 and 2, and is adapted to fit within a shoe and to receive 60 the arch of the foot and support such arch while the shoe is worn. The support is merely placed in the shoe so that it is removable at any time for the purpose of altering the size of the support in the manner 65 hereinafter described.

As shown in Fig. 1, the arch support proper is indicated at 1, and 2 and 3 designate side flaps projecting from the lateral edges of the support 1 and arranged to be 70 bent up about the sides of the central portion of the foot so that the support conforms substantially to the curvature of the foot and is in contact with the arch of the foot throughout in order to sustain it at 75 all points.

At the rear end, the arch support 1 is connected to a heel piece 4 which is adapted to lie, when the support is placed within a shoe, at the heel portion of the shoe, in order 80 that the heel of the wearer may rest upon this heel piece 4. The weight of the wearer resting on the heel piece 4 will serve to effectually anchor the arch support in place and prevent its accidental displacement 85 from the correct position in the shoe, as it is only in such position that correction of the feet may be had.

The improved support, broadly speaking, is built up of longitudinally and transversely arranged springs mounted in pockets carried by a body portion which is preferably made up of a series of layers of leather or other suitable material.

As shown more particularly in Figs. 3 and 95 4, 5 designates the base layer of leather which rests upon the bottom lining of the shoe, 6 represents an intermediate layer, and 7 a top layer or facing upon the upper surface on which the foot is adapted to rest. 100 These layers or laminations 5, 6 and 7 are extended laterally to form the side flaps 2

and 3, and rearwardly to form the heel piece 4, and, as shown in Fig. 3, there is interposed a pad of rubber or other resilient material 8 between the layers 5 and 6 with-
5 in the heel piece 4. This rubber pad 8 acts as a cushion yielding increased flexibility, thus accommodating the support to the arch of the foot more comfortably.

As shown in Fig. 4, longitudinal lines of
10 stitching 9 are made through the layers 5 and 6 at spaced intervals, in order to provide pockets 10 between such lines of stitching 9 and between the layers 5 and 6. These pockets are provided to receive longitudinal
15 springs or strips of resilient metal 11, which have their ends resting upon metallic or other plates 12 and 13, likewise laid in pockets 14 and 15 formed at the forward and rear portions of the arch support and made, in this instance, by depressing the
20 lower layer 5 in the manner shown in Fig.
3. These pockets 14 and 15 extend transversely of the arch support, and the manner in which the longitudinal springs 11 rest
25 thereon is clearly shown in Figs. 2 and 3.

A line of stitching 16 is made between the heel piece 4 and the pocket 14, and this line of stitching also extends through the upper layer 7, as clearly shown. Furthermore, the
30 heel piece is stitched, as indicated at 17, about its rear and lateral edges, this line of stitching 17 passing through the lower and upper layers 5 and 7 only, as appears in Fig. 3. The stitching 17 closes the heel
35 piece and confines the cushion 8 therein.

In a similar manner the intermediate layer 6 is secured to the upper layer 7 by separated lines 18 of transversely running stitching, such lines being arranged in
40 spaced apart pairs in order to form pockets 19 between the layers 6 and 7, such pockets extending in a transverse direction and preferably being given the fan-shaped form indicated in Figs. 1, 2, 3.

45 Flat metallic bars or springs 20 are received into the pockets 19, and are bent at their opposite ends where they enter the flaps 2 and 3, such bent ends serving to hold the flaps in the proper positions. A
50 line of stitching 21, passes about the arch support in order to secure the layers together in any suitable manner, but this stitching may be omitted along one side and the front of the arch support in order to
55 leave the ends of the pockets 10 and 19 open for receiving and withdrawing the springs 11 and 20 therefrom. One of these springs is shown in Fig. 5, the preferred form being a flat bar or resilient metal having the
60 rounded ends 22 and 23 to facilitate insertion into the mouths of the pockets and to present a smooth finish in order not to cut the leather.

In use, the device is assembled in the

manner shown in Figs. 1 to 4, and the assembled device presents the appearance indicated in Fig. 1, where the complete device is shown ready to be inserted within the shoe. The device shown in Fig. 1 is intended for the right foot, and the enlarged flap 2 held in place by the bent ends of the transverse springs 20 arranged to embrace the instep of the foot while the flap 3 projects only slightly to brace the outer side of
75 the arch.

The device may be built up of any number of the longitudinal or the transverse springs, and if desired, the transverse springs may be removed through the open mouths of the pocket 19 and the support used only with the longitudinal springs 11; or the longitudinal springs 11 may be withdrawn from the pockets 10 and the device used only in connection with the transverse springs 20. Again, certain of either or both the transverse and longitudinal springs may be withdrawn while others remain, and the device used in this condition. In other words, the springs may be added to or diminished to meet the requirements of each individual foot. The cross springs are so constructed that they also brace the arch of the foot from the side as well as the bottom. Of course the device may be added to by increasing the number of layers of leather used, and stitching the same in the manner already shown, to provide additional pockets for further series of springs.

In Fig. 6, a main spring 30 is provided with clips 31 and 32 to hold one or more auxiliary springs 33. This structure forms a laminated spring useful in place of the flat springs 11, and the flexibility of which may be varied by increasing or decreasing the number of the auxiliary springs 33.

It is obvious that those skilled in the art may vary the details of construction and arrangements of parts without departing from the spirit of my invention, and therefore I do not wish to be limited to such features except as may be required by the claims.

I claim:

1. An improved arch support including a body portion composed of three layers of suitable material, the upper and intermediate layer having transverse pockets formed therebetween, flat springs removably fitted in said transverse pockets, longitudinal pockets formed between said lower and intermediate layers, flat springs removably fitted in said longitudinal pockets, means for supporting the ends of said longitudinal springs, and side flaps on said body portion into which the transverse springs extend, substantially as described.

2. An improved arch support including a body portion and a heel extension both

made up of three layers of suitable material, longitudinal and transverse pockets formed respectively between the lower and intermediate and the upper and intermediate layers on the body portion, flat springs 5 removably placed in said pockets, plates lying between said lower and intermediate

layers and adapted to support the ends of said longitudinal springs, and a resilient pad placed between the lower and intermediate layers in the heel piece, substantially as described. 10

SAMUEL DARLING.
